WOOD-HEEL CUPPING MACHINE

Wilfred J. Grenier, North Rutland, Mass.

Application February 3, 1949, Serial No. 74,437

18 Claims. (Cl. 144—145)

1

The present invention relates to improvements in wood-working machines and more particularly, to improvements in wood-heel cupping machines.

The primary object of the present invention is to provide a machine for automatically cupping the upper faces of wood-heel blanks in a manner which will enable this work to be performed by unskilled labor; the machine being adapted successively to clamp the blanks, as they are fed to the machine, and to hold them in place during the cupping operation, and thereafter, automatically discharging them at the end of the cupping cycle.

A further object of the present invention is to provide a machine of the above noted type which is so designed that it may be quickly and easily adapted for the automatic cupping of different size wood heels by relatively unskilled persons.

A further object of the present invention is to provide an automatic cupping machine which will be not only efficient in operation but which, at the same time, will be relatively inexpensive of manufacture.

A still further object of the present invention is to provide the machine of the above noted type which, although fully automatic in operation, is, at the same time, designed in a manner such that it may be readily serviced and repaired with a minimum expenditure of time and effort.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the accompanying drawings,

Fig. 1 represents a top plan view of the present machine.

Fig. 2 represents a sectional view of the present machine taken substantially along the line 2—2 of Fig. 1.

Fig. 3 represents, on an enlarged scale, a top plan view of a blank-gripping mechanism.

Fig. 4 represents, on an enlarged scale, a sectional view through an air valve mechanism, which view is taken substantially along the line 4—4 of Fig. 1.

Fig. 5 represents, on an enlarged scale, a sectional view through an air valve mechanism,

2

which view is taken substantially along the line 5—5 of Fig. 1.

Fig. 6 represents a perspective view of a typical type of wood-heel blank which is operated on by the present machine.

Figs. 7, 8 and 9 represent, respectively, top, side and end views of the wood-heel blank as it is discharged from the machine upon the completion of the cupping operation.

Fig. 10 represents, on an enlarged scale, a perspective view of a conveyor mechanism which may be used in conjunction with the present machine, for the purpose of successively placing a plurality of wood-heel blanks within the various blank-gripping mechanisms carried upon the machine.

Fig. 11 represents, on an enlarged scale, a right-hand end view of the machine disclosed in Fig. 1, with the conveyor mechanism which is disclosed in Fig. 10, secured in its operative position, and illustrating the air cylinder portion of this mechanism in longitudinal section.

Fig. 12 represents, on an enlarged scale, an end view of a modified form of pattern element which is adapted to be adjusted so as to accommodate the machine for the production of various size wooden heels.

Fig. 13 represents a sectional view of the device disclosed in Fig. 12, which sectional view is taken substantially along the line 13—13 of Fig. 12.

Fig. 14 represents a sectional view taken substantially along the line 14—14 of Fig. 13.

Fig. 15 represents a sectional view taken substantially along the line 15—15 of Fig. 1.

Fig. 16 represents a perspective view of a portion of the adjusting mechanism disclosed in Fig. 15.

Fig. 17 represents a sectional view taken substantially along the line 17—17 of Fig. 3.

As hereinabove noted, Fig. 6 represents a wooden heel blank 15 of the type which is fed to the present machine. It will be observed that such a blank is substantially rectangular in shape. The present machine, as above indicated, is adapted to perform a so-called cupping operation upon the blanks, which operation consists in cutting the upper face of the blank in a manner as is particularly illustrated in Figs. 7, 8 and 9. In other words, the upper face of the blank 15 is cut so as to provide a substantially concave surface 16, which surface will support directly the under portion of a shoe, after the blank has been completed by turning each 55 of the opposite side portions of the blank in a

well-known manner. Shoes employing heels of the present type are known in the trade by the term "wedges."

The present machine comprises a pair of laterally spaced upright arm members 17 and 18, each of which is pivotally supported at its lower portion upon a horizontally disposed shaft 19. These shafts 19, 19 may be journaled within bearing blocks 20 which may be suitably secured upon the floor. The upper end portions of the arms 17 and 18 are adapted to receive the opposite end portions of a rotatable shaft 21. Mounted upon the shaft 21 is a cylindrical drum structure 22 which is adapted to carry a plurality of blank clamping elements, each of which is generally designated by the numeral 23.

The right-hand end portion of the shaft 21, as viewed in Fig. 1, projects through the arm 17 and into a gear box 24. As may be best understood by reference to Figs. 1 and 2, the end portion of the shaft 21 carries a worm wheel 25 which meshes directly with a worm 26 journaled within the end walls of the gear casing 24. The gears 25 and 26 function as a speed reduction unit, and the latter gear is driven by means of an electric motor 27 through the medium of a pair of pulleys 28 and 29 and a belt 30 connecting said pulleys. From this, it will be appreciated that upon energization of the motor 27, the drum 22 will rotate in a predetermined direction at a speed which is substantially less than that of the motor shaft. In the present machine, the drum or cylinder 22 is adapted to rotate in a clockwise direction, as viewed in Fig. 2. The motor 27 is secured directly upon a flange 31 which, in turn, is mounted upon the outside face of the arm 17. Suitable leads, not herein shown, function to connect the motor 27 to a suitable source of electrical energy.

Referring particularly to Figs. 1, 2 and 3, it is to be noted that the cylinder 22 has spaced about its peripheral portion, six of the above noted clamping elements 23, 23. Each of these mechanisms includes a stationary jaw member 32 which is rigidly secured to the peripheral portion of the cylinder by any suitable means. As may be particularly seen in Fig. 3, the jaw member 32 is provided with a recessed face portion 33 which is adapted to receive a wood-heel blank 15. A movable jaw element 34 is carried upon the end portion of a piston rod 35 and is adapted to engage one edge portion of the blank 15 for the purpose of locking the same within the confines of the jaw recess 33. The other end portion of the piston rod 35 extends into an air cylinder 36, and is secured directly to a piston element 37. An air hose 38 is attached to the left-hand end portion of the cylinder 36 for the purpose of supplying air, under pressure, to the cylinder, which air will urge the piston 37 and, consequently, the jaw 34 in a right-hand direction against the action of a coil spring 39 which surrounds an intermediate portion of the piston rod 35. In order to permit the free movement of the piston 37, the right-hand end portion of the cylinder is provided with an aperture 40. From the above, it will be readily appreciated that the spring 39 will normally hold the jaw 35 in its open left-hand position, and that whenever air, under pressure, gains entrance into the cylinder by way of the hose 38, the jaw 34 will be forced in a right-hand direction, to the end that a heel blank 15 will be clamped in its operative position.

Surrounding the above noted cylinder or drum mechanism is a substantially rectangular shaped

open framework which includes front and rear members 41 and 42 and a pair of connecting side members 43 and 44. These various frame members may be welded, or otherwise suitably secured together, and for supporting them, there are provided four vertically disposed end posts 45, 45, the lower end portions of which may be secured to the floor in any appropriate manner. Projecting downwardly from the rear frame member 42 are a pair of bearing members 46 and 47 which are adapted to support the opposite end portions of a rotatable cutter shaft 48 in a manner as best disclosed in Figs. 1 and 2. An intermediate portion of the shaft 48 carries a cutting tool 49 which is adapted to perform the above described cupping operation in a manner which will be hereinafter described in more detail. Referring particularly to Fig. 1, it is to be noted that the right-hand distal end portion of the shaft 48 carries a pulley 50 which is connected with a drive pulley 51 by means of a belt 52. Since the pulley 51 is carried upon the armature shaft of an electric motor 53, it is manifest that rotation of the motor will function to drive the cutter 49. In the present machine, the cutter 49 is adapted to rotate in a clockwise direction, as viewed in Fig. 2.

Projecting downwardly from the front frame member 41 is an angle flange member 54 which is designed to carry a pattern element or cam 55. As may be particularly noted in Fig. 2, the active face portion 55' of the pattern element is adapted to be successively engaged by wheels 57, 57 carried upon the right-hand face portion of the cylinder 22. More specifically, each of the wheels 57, 57 is rotatably mounted upon a shaft 58 which, in turn, is carried by the cylinder 22. Still referring to Figs. 2, it will be observed that each of the wheels 57, 57 is disposed adjacent a respective one of the blank clamping elements 23, 23, so that whenever the wheel element engages a raised portion 59 of the pattern element 55, the cylinder member 22 will pivot with the arm members 17 and 18 about the shafts 19, to the end that a blank member 15 carried within one of the clamping mechanisms, will be urged against the cutter element 49. Thus, it will be appreciated that the shape of the active portion 55' of the pattern element 55 determines the manner in which the cutter 49 will shape the wood-heel blanks. As noted in Fig. 1, the cutter 49 is shaped so as to form a concavity within the outer surface of the blank, and the portion 59 on the pattern element 55 is so disposed that the face of the blank will be curved in a manner as disclosed particularly in Fig. 8. The motor 27 functions to rotate the cylinder 22 to the end that each of the clamping mechanisms 23, 23 is successively presented to the cutter element 49 which is, in turn, rotated by the motor 53. A spring 56 may be attached to the arm 17 for urging the wheels 57, 57 positively at all times against the pattern element 55.

Each of the blank-gripping mechanisms 23, 23 is adapted to receive a wood-heel blank when the mechanism is at the highest point in its path of rotation, and after the cupping operation has been completed and the gripping mechanism is disposed at a location adjacent the bottom portion of its path of travel, it is adapted to discharge the finished blank so that the latter will drop either into a tote box or upon a moving conveyor belt.

For so controlling the actions of the gripping mechanisms, the present invention contemplates

the provision of an automatic air valve which is generally designated by the numeral 60. Referring particularly to Figs. 1, 4, and 5, this air valve comprises a stationary member 61 which surrounds the left-hand end portion of the shaft 21, and has its left-hand face portion secured directly to the arm member 18. Cooperating with the member 61 is a portion 62 which surrounds and is secured to the shaft 21 so as to rotate in synchronism therewith. However, as will be particularly observed in Fig. 1, the respective face portions 63 and 64 of the members 61 and 62 are disposed in intimate contact with each other and are adapted to rotate relative to each other during the operation of the machine. The member 61 has an arcuate groove 65 formed in its face 63 and communicating with this groove, is an inlet aperture 66 which may be connected to an air pump 67 by means of a flexible air hose 68. It will be understood that the aperture 66 extends through the arm 18 so as to be suitably connected with the hose 68. A suitable type of electric motor 69 may be connected with the pump 67 for the purpose of furnishing air, under pressure, to the groove 65 at all times during the operation of the machine.

Also formed within the face 63 of the member 61 is a second arcuate groove 70 which is connected with the atmosphere by means of an aperture 71 which passes directly through the arm 18 so as to be connected with a short exhaust tube 72.

The portion 62 of the air valve is suitably coupled directly to the shaft 21, and its face 64 is provided with a plurality of apertures 73, 73 which are so located thereabout that they will communicate with the arcuate grooves 65 and 71 of the member 61, as the member 62 rotates relative to the member 61. As may be particularly noted in Fig. 1, each of the apertures 73, 73 may be connected with a respective one of the air cylinders 36, 36 by means of a flexible hose 38. From this, it will be appreciated that as the member 62 rotates in synchronism with the shaft 21, the various apertures 73, 73 will be alternately connected with the pressure chamber or groove 65 and the exhaust chamber or groove 70, to the end that the movable jaws 34, 34 will be actuated in a proper sequence. More specifically, the arcuate grooves 65 and 70 are so disposed about the stationary valve member 61 that each of the jaw elements 34, 34 will be closed whenever its associated clamping mechanism is disposed at the highest point in its path of rotation. Thereafter, the jaw member will remain closed until the clamping mechanism passes by the rotary cutter 49 and is disposed at a location adjacent the lowest point in its path of travel. At this juncture, the jaw will open and thus, the completed wood-heel blank will drop under the force of gravity into either a tote box or upon a moving conveyor belt.

In other words, whenever one of the apertures 73, 73 communicates with the pressure chamber or groove 65, air, under pressure, will enter the air cylinder, to the end that its piston 37 will move in a right-hand direction against the action of the spring 39. Obviously, the piston 37 will remain in this position until its associated aperture 73 communicates with the exhaust chamber or groove 70, at which juncture the air, under pressure, within the cylinder, will exhaust itself through the opening 71 so that the spring 39 will then move the piston 37 in a left-hand direction so as to open the jaw 34 and release the completed

wood heel. From this, it will be appreciated that the jaw will remain open until after its associated aperture 73 again communicates with the pressure chamber 65.

From the above, it will be appreciated that the entire working cycle of the present machine is fully automatic, and that in one form of the device, it is merely necessary for the operator to place the rectangular shape heel blanks 15 successively within the moving gripping mechanisms 23, 23, for the remaining operations are fully automatic. However, as hereinafter described in further detail, the present machine may be provided with an automatic loading mechanism, in which case the operator need merely supply the loading mechanism with the blanks in a manner which requires absolutely no skill. Furthermore, it will be appreciated that the pattern element 55 may be readily removed from its flange 54 by loosening the holding bolts 74, 74. Thus, within a few minutes, the pattern element 55 may be removed and a new pattern element placed in position, so that the machine will be adapted to produce heel blanks of a different size.

As hereinabove mentioned, the present invention contemplates the provision of a means whereby the above described machine may be automatically loaded with wood-heel blanks. Referring particularly to Figs. 10 and 11, there is disclosed a pair of laterally spaced rollers 75 and 76, each of which is mounted upon a respective one of a pair of shaft elements 77 and 78, the opposite end portions of which may be rotatably journaled within the upstanding side members 79 and 80 of a sheet metal framework designated by the numeral 81. An endless belt 82 may be trained over the rollers 75 and 76, and for rotating this belt in a clockwise direction, as viewed in Fig. 10, the distal end portion of the roller shaft 77 may be provided with a belt pulley 83. An electric motor, not herein shown, may be provided for rotating the pulley 83 through the medium of a belt 84. As is particularly disclosed in Fig. 11, the framework 81 may be secured to the horizontal arm 43 of the machine frame by means of a plurality of bolts 85, 85.

Referring both to Figs. 10 and 11, it is to be noted that the side portions 79 and 80 of the framework 81 project upwardly above the upper surface of the endless belt 82 so as to function as guide elements. Furthermore, the right-hand end portion of the framework is provided with a channel guide generally designated by the numeral 86 which is disposed directly in line with the rotating gripping mechanisms 23, 23. Thus, an operator may deposit the wooden blanks 15, 15 upon the left-hand end portion of the conveyor mechanism, as viewed in Fig. 10, and thereafter, the endless belt 82 will function to deliver these blocks to the right-hand end portion of the mechanism, at which point the end block will be in direct alignment with the work guide means 86. Thus, if this end block were to be urged lengthwise along the guide 86 and away from the conveyor mechanism in proper synchronism with the rotation of the drum 22, it will be appreciated that the block could be deposited between the movable and stationary jaws of one of the work gripping elements 23, 23. In order to accomplish such an objective, the present conveyor mechanism is provided with an air cylinder 87 which is secured to one side of the conveyor mechanism by means of a flange 88. This air cylinder is provided with a piston 89 and a piston rod 90, the right-hand end portion of which is aligned

with the guide means 86 and an aperture 91 provided within the framework of the conveyor. The left-hand portion of the cylinder 87 is provided with an air hose 92 which may also be connected with the air pump 67. Thus, if air, under pressure, is delivered to the left-hand end portion of the cylinder 87, the piston rod 90 will move in a right-hand direction so as to urge one of the wood-heel blanks through the guide means 86.

As hereinabove noted, the jaw elements of the gripping mechanisms 23, 23 are in an open condition until they reach the highest point in their path of travel, after which the valve mechanism 60 functions to close the jaws. From this, it will be appreciated that the piston rod 90 should be synchronized with the motion of the drum 22, so that a wood-heel blank 15 may be inserted within the open gripping jaws of each clamping mechanism just prior to the closing of the latter. In order to accomplish this objective, the present invention contemplates the provision of a three-way valve mechanism 93 which may be mounted upon the top portion of the oscillating arm 17 by means of a flange 94. This valve mechanism may be of a usual commercial type which is provided with an actuating lever 95 which is normally biased into its closed position by means of a leaf spring 96. This handle member 95 is so positioned that it will be engaged by each of the roller members 57, 57 as the drum 22 rotates in a clockwise direction, as viewed in Fig. 11. From this, it will be appreciated that such a valve 93 may be connected with the air line 92 so as to fill the piston 87 with air under pressure, whenever the valve is tripped by a respective one of the rollers 57, 57. After the roller has released the handle 95, it will be effective to exhaust the cylinder 87 so that the piston 89 may be re-turned in a left-hand direction under the action of a coil spring 97 provided within the cylinder. Thus, as soon as the piston rod 90 is retracted into the cylinder 87, a fresh wood-heel blank will move into place against the end portion of the conveyor or guide wall. From the above, it will be readily appreciated that the present conveyor mechanism is most simple and effective, for it will relieve an operator of the rather tedious job of endeavoring to place a single heel blank within each of the gripping mechanisms 23, as the same comes up into its heel-receiving position. Since the present machine is adapted to operate at a relatively high speed, it will be appreciated that without the present conveyor mechanism, an operator would soon be subject to extreme fatigue. However, an operator may easily remove heel blanks from a tote box and place them upon the conveyor belt 82 with the expenditure of very little effort. As a matter of fact, an operator may place several heel blanks upon the conveyor belt 82 at once and obviously, no special care need be exercised in the placing of the blanks upon the conveyor belt, as compared to the rather accurate work required in placing such a blank within the heel gripping mechanisms 23, 23.

As hereinabove noted, the pattern element 55 can be removed from the machine and replaced with a different pattern element, for the purpose of varying the shape of the work produced on the machine. However, the present invention also contemplates the provision of a pattern element, the shape of which may be varied by a relatively simple hand operation, to the end that the pattern element need not be removed from the machine in order to vary the shape of the work produced. Such a form of pattern element will

5 save much time and effort whenever the machine is to be changed over for the production of a different type heel. For example, with the modified form of pattern element, it is merely necessary for the operator to make several adjustments, each of which may be made in accordance with an instruction sheet or chart, to the end that a relatively unskilled operator may set up the present machine for the production of different type heels. More specifically, the present modified form of pattern element is illustrated in Figs. 12, 13 and 14. Briefly stated, this device comprises a flexible strip of material 98, one surface of which is adapted to function as a cam or template surface against which the various rollers 57, 57 may abut. In other words, the one surface of the strip 98 corresponds to the active surface 55' of the pattern element 55. Means are provided with this modified form of pattern element whereby the contour of the strip 98 may be varied so as to form any needed type of cam surface, to the end that an operator may vary such surface so as to adapt the machine for producing heel blanks of various shapes.

20 25 30 35 40 45 More specifically, the present modified pattern element comprises a metallic block 99 which may be milled so as to form an arcuate groove 100 and a plurality of grooves 101, 101 which are disposed in a fan-like fashion so as to receive therein a plurality of tongue elements 102, 102. A plate member 103 may be suitably secured over the member 99 so as to cover the groove 100 and confine the various tongues 102, 102 within their respective grooves 101, 101. The flexible strip 98 may be welded or otherwise secured at its upper end to a portion of the member 99, while its intermediate portions are spring biased inwardly against the ends of the various tongues 102, 102. In order to so bias the strip 98, the pattern element is provided with a plurality of hooks 104, 104 which are so disposed upon either side of the pattern that they will engage the opposite marginal edge portions of the strip 98. The inner edge portions of each of the hooks 104, 104 is connected with one end of a coil spring 105, the other end portion of which is secured to an abutment member 106 provided upon the member 99.

50 55 60 65 70 75 Threaded into the back wall portion 107 of the member 99 are a plurality of hand screws 108, 108 in a manner so that each of these screws will be axially aligned with a respective one of the tongues 102, 102. As may be noted in Fig. 12, the screws 108, 108 are disposed in a staggered relation within the back wall 107 so as to afford proper clearance therebetween. From this, it will be understood that each of the screws 108, 108 may be individually adjusted by hand, to the end that the contour of the flexible strip 98 may be varied. Thus, by adjusting the screws 108, 108 back and forth, any desired contour of the strip 98 may be obtained, to the end that any desired shape may be produced on the wood-heel blanks 15, 15. The entire adjustable pattern mechanism may be mounted upon the angle bracket 54 by means of a pair of bolts 109, 109 which are received in the apertures 110, 110, so as to be threaded directly within the angle bracket 54 in the same relative position as the pattern element 55 which is disclosed in Fig. 2. Thus, when it is necessary to set up the present machine for the production of different size wood-heel blanks, it is merely necessary for the operator to vary the contour of the flexible strip 98 by means of the adjusting screws 108, 108. The present adjust-

able cam means may be provided with some form of indicator so that the operator may adjust the various screws 108, 108 within predetermined limits, according to an instruction sheet which may be furnished with the machine. Such a cam may be adjusted by an unskilled operator, to the end that the machine set-up time is greatly reduced.

In order to further reduce the set-up time of the present machine, the present invention contemplates the provision of a plurality of back stop members 111, 111, each of which is associated with a respective one of the wood-heel clamping mechanisms 23, 23. More specifically, and with particular reference to Figs. 3, 11 and 17, it is to be understood that the rear portion of each of the stationary jaw elements 32, 32 is provided with a slot 112 for receiving therein an adjustable back stop element 111, one end portion of which is adapted to serve as an abutment member or stop for the heel blank 15, so that the blank may be inserted between the jaws 32 and 34 a predetermined distance, depending upon the size of the heel to be produced. The other end portion of each of the stop members 111, 111 is bent so as to be disposed radially of the rotating drum 22. As may be particularly noted in Figs. 1 and 11, each of these inner end portions 113 of the stop members 111 extends radially of the drum 22 through an aperture 114 in the drum wall, while the extreme inner end portion thereof extends longitudinally of the drum so as to be rigidly secured upon the inner face of an adjusting ring 115 carried upon the right-hand end portion of the drum. This adjusting ring 115 is slidably mounted upon an inner ring 116 rigidly secured to the drum by means of a plurality of screws 116', 116'. Since each of the inner end portions of the radial members 113, 113 extend through a respective one of a group of apertures 117, 117 provided in the drum, it will be appreciated that the adjusting ring 115 may be rotated back and forth about the ring 116 so as to shift the adjustable stops 111, 111 relative to their associated jaw members 32, 32. As may be noted in Fig. 11, the adjusting strip 115 has an abutment 118 disposed thereon for the purpose of functioning as a handle and, at the same time, the drum end is provided with appropriate indicia 118' so that the operator may shift the strip 115 a predetermined distance in either a clockwise or counterclockwise direction, for the purpose of altering the position of each of the heel blanks within their respective gripping mechanism. Bolts 115', 115' passing through elongated slots 119, 119 function to lock the ring 115 in any desired position of adjustment.

It will be understood by those skilled in the art that as the size of the various heels vary, it is necessary to alter the angle of the cupping cut relative to the bottom or flat portion of the heel. In order to vary this angle, the present invention contemplates the provision of an adjustable wood-heel blank support. With particular reference to Figs. 3, 15, 16 and 17, it is to be noted that a wood-heel blank support member 120 is disposed within the recess 33 of the stationary jaw member 32. Also, each of these support members 120, 120 is pivotally secured to its associated jaw member 32 by means of a pin 121. Thus, the rear portion of each of the support members 120, 120 may be raised and lowered relative to its associated jaws. By so adjusting the support member or platform 120, it will be understood that the angle between the bottom

portion of the heel blank and its cupping contour will be altered.

In order to adjust each of the platform members 120, 120 simultaneously, each is provided at its lower rear portion with a link member 122, 122. Each of these links 122, 122 is pivotally connected at its inner end to a respective one of a plurality of transverse rods 123, 123 which are disposed between a pair of disk elements 124 and 125. As may be noted particularly in Figs. 15 and 16, the inner disk element 125 is provided with an apertured hub 126 which is rotatably mounted upon the shaft 21, while the other disk 124 is adjustably secured against the left-hand end portion of the drum 22. Each of the rods 123, 123 extends through an aperture 127 provided in the drum end so that as the disk 124 is rotated back and forth, it will function to raise or lower each of the support members 120, 120. The disk 124 may be secured to the drum end by means of a plurality of bolts 128, 128, each of which passes through an elongated slot 129 provided within the disk 124. Thus, a limited turning movement may be imparted to the disk, to the end that all of the support members 120, 120 may be adjusted up or down simultaneously. Formed on the peripheral portion of the disk 124 is a handle member 130 which may be used by the operator for adjusting the above noted mechanism, while the drum end may be provided with appropriate indicia 131 which cooperates with the handle member 130 so as to indicate the amount of movement imparted to the disk 124.

From the above, it will be appreciated that in the event it is necessary to alter the present machine for the purpose of accommodating it to produce different size heels, it is merely necessary to furnish the operator with an appropriate chart so that the operator may adjust the pattern element 35, the back stop elements 111, 111, and the support elements 120, 120, according to the information contained on the chart. In other words, the various screws 108, 108 of the pattern element may be turned a predetermined distance 40 so as to produce a desired contour on the flexible strip 98, while each of the rings 115 and 124 may be rotated a predetermined distance, all for the purpose of accommodating the machine for the production of different size wood-heel blanks. 45 Obviously, these three adjustments may be made by an unskilled operator for he merely need make these adjustments in accordance with the instructions contained on a chart, and no particular mechanical skill is required. Furthermore, it will be appreciated that these three adjustments may be quickly made and thus, the machine may be ready for the accommodation of different size heel blanks within a few minutes. 50 In this connection, as those skilled in the art well know, it has been necessary, when using prior art types of machines, for an operator to spend two or three hours in changing over a machine from one set-up to another. Obviously, the present machine is so designed so that an operator may cut this set-up time down from several hours to a few minutes, thus making it economically feasible to utilize a fully automatic machine in the production of wood-heel blanks, even though the actual number of blanks to be produced for any one job is relatively small. In other words, the present machine can be adjusted in such a short time that it can produce economically within an eight-hour day, several orders of 55 different type wood-heel blanks, even though the

actual number of blanks making up each order is relatively small.

I claim:

1. A wood shaping machine comprising, a cutter rotatably mounted about a fixed axis, a plurality of work-holding clamps, a carrier for supporting all of said clamps for rotation in unison about a first axis disposed substantially in parallelism with the axis of said cutter, with said clamp carrier being mounted about a second axis laterally spaced from and disposed in parallelism with said first axis, means for opening and closing said clamps in a predetermined cycle, means for rotating said carrier to move said clamps about said first axis and past said cutter, and means effective to oscillate said carrier with said clamps about said second axis thereby to control the cutting action of the cutter upon the work carried by the clamps.

2. A wood shaping machine comprising, a cutter rotatably mounted about a fixed axis, a plurality of work-holding clamps, a carrier for supporting all of said clamps for rotation about a common first axis disposed in parallelism with the axis of said cutter, with said clamp carrier being mounted about a second axis laterally spaced from and disposed in parallelism with said first axis, means for opening and closing said clamps in a predetermined cycle, means for rotating said carrier to move all of said clamps in synchronism about said common first axis and past said cutter, and cam means effective to oscillate said carrier with said clamps about said second axis thereby to control the cutting action of the cutter upon the work carried by the clamps.

3. A wood shaping machine comprising, a cutter rotatably mounted about a fixed axis, a plurality of work-holding clamps, a carrier for supporting all of said clamps for rotation about a common first axis disposed substantially in parallelism with the axis of said cutter, with said clamp carrier being rockably mounted about a common second axis laterally spaced from and disposed in parallelism with said first axis, means for opening and closing said clamps in a predetermined cycle, means for rotating said carrier to move all of said clamps in synchronism about said first axis and past said cutter, and means effective to oscillate said carrier with all of said clamps in synchronism about said second axis thereby to control the cutting action of the cutter upon the work carried by the clamps.

4. A wood shaping machine comprising, a cutter rotatably mounted about a fixed axis, work-carrying means rotatably mounted about a first axis disposed substantially in parallelism with the axis of said cutter and rockably mounted about a second axis laterally spaced from and disposed in parallelism with said first axis, a plurality of work-holding clamps mounted on said work-carrying means, means for opening and closing said clamps in a predetermined cycle, means for rotating said work-carrying means about said first axis so as to present each of said clamps to said cutter, and means effective to oscillate said work-carrying means about said second axis thereby to control the cutting action of the cutter upon the work carried by each of said clamps.

5. A wood shaping machine comprising, a cutter rotatably mounted about a fixed axis, work-carrying means rotatably mounted about a first axis disposed substantially in parallelism with the axis of said cutter and rockably mounted about a second axis laterally spaced from and disposed in parallelism with said first axis, a plu-

rality of work-holding clamps mounted on said work-carrying means for securing a plurality of work pieces upon said work-carrying means, means for opening and closing said clamps in a predetermined cycle, means for rotating said work-carrying means about said first axis so as to present each of said clamps to said cutter, and cam means effective to oscillate said work-carrying means about said second axis so as to control the relative spacing between each of said work clamps and said cutter thereby to control the cutting action of the cutter upon the work carried by each of said clamps.

6. A wood shaping machine comprising, a pair of arms pivotally mounted about a common axis, a work-carrying member rotatably mounted between said arms and about an axis spaced from and in parallelism with the common pivotal axis of said arms, means for rotating said work-carrying member about its axis of rotation, a plurality of work-holding clamps mounted on said work-carrying member for securing a plurality of work pieces upon said member, means for opening and closing said clamps in a predetermined cycle, a cutter rotatably mounted adjacent the periphery of said work-carrying member, and means for oscillating said arms back and forth about said common pivotal axis thereby to control the cutting action of the cutter upon the work carried by each of said clamps.

7. A wood shaping machine comprising, a pair of arms pivotally mounted about a common axis, a work-carrying member rotatably mounted between said arms and about an axis spaced from and in parallelism with the common pivotal axis of said arms, means for rotating said work-carrying member about its axis of rotation, a plurality of work-holding clamps mounted on said work-carrying member for securing a plurality of work pieces upon said member, means for opening and closing said clamps in a predetermined cycle, a cutter rotatably mounted adjacent the periphery of said work-carrying member, cam-engaging means carried by said work-carrying member, and a stationary cam member engageable with said cam-engaging means thereby to cause said arms to oscillate about said common pivotal axis so as to control the cutting action of the cutter upon the work carried by each of said clamps.

8. A wood shaping machine comprising, a pair of vertically disposed arms pivotally mounted at their lower end portions about a common horizontal axis, a work-carrying member rotatably mounted between the upper end portions of said arms and about a horizontal axis, a plurality of work-holding clamps mounted on said work-carrying member for securing a plurality of work pieces upon said member, means for opening and closing said clamps in a predetermined cycle, a cutter rotatably mounted adjacent the periphery of said work-carrying member, means for rotating said cutter, means for rotating said work-carrying member about its horizontal axis so as to present each of the work pieces to said cutter, cam-engaging means carried by said work-carrying member, and a stationary cam member engageable with said cam-engaging means thereby to cause said arms to oscillate about said common pivotal axis so as to control the cutting action of the cutter upon the work carried within each of said clamps.

9. A wood shaping machine comprising, a pair of arms pivotally mounted about a common axis, a work-carrying member rotatably mounted between said arms and about an axis spaced from

and in parallelism with the common pivotal axis of said arms, a plurality of fluid-operated work-holding clamps mounted on said work-carrying member for securing a plurality of work pieces upon said member, valve means operated by the relative rotative movement between said work-carrying member and said arms for opening and closing said clamps in a predetermined cycle, a cutter rotatably mounted adjacent the periphery of said work-carrying member, means for rotating said cutter, means for rotating said work-carrying member so as to present each of the work pieces to said cutter, cam-engaging means carried by said work-carrying member, and a stationary cam member engageable with said cam-engaging means thereby to cause said arms to oscillate about said common pivotal axis so as to control the cutting action of the cutter upon the work carried by each of said clamps.

10. A wood shaping machine comprising, a substantially cylindrical shaped work-carrying means rotatably mounted about its longitudinal axis and rockably mounted about a second axis laterally spaced from and disposed in parallelism with said longitudinal axis, a cutter rotatably mounted about a fixed axis disposed adjacent the periphery of said work-carrying means, a plurality of work-holding clamps circumferentially spaced about the periphery of said work-carrying means, means for opening and closing said clamps in a predetermined cycle, means for rotating said work-carrying means about said longitudinal axis so as to present each of said clamps to said cutter, and cam means effective to oscillate said work-carrying means about said second axis so as to control the cutting action of the cutter upon the work carried by each of said clamps.

11. A wood shaping machine comprising a pair of arms pivotally mounted about a common axis, a work-carrying member rotatably mounted between said arms and about an axis spaced from and in parallelism with the common pivotal axis of said arms, a cutter rotatably mounted adjacent the periphery of said work-carrying member, means for rotating said cutter, a plurality of work-holding clamps mounted on said work-carrying member for securing a plurality of work pieces upon said member, means for rotating said work-carrying member about its axis of rotation thereby to present each of the work pieces to said cutter, means for oscillating said arms back and forth about said common pivotal axis thereby to control the cutting action of the cutter upon the work pieces, fluid-operated means for opening and closing said clamps, fluid operated feeding means for successively inserting a work piece within each of the open clamps, and means responsive to the relative movement between said work-carrying member and said arms for controlling both of said fluid-operated means.

12. A wood shaping machine comprising, a cutter rotatably mounted about a fixed axis, a plurality of work-holding clamps, a carrier for supporting all of said clamps for rotation in unison about a first axis disposed substantially in parallelism with the axis of said cutter, with said clamp carrier being mounted about a second axis laterally spaced from and disposed in parallelism with said first axis, means for opening and closing said clamps in a predetermined cycle, means for rotating said carrier to move said clamps about said first axis and past said cutter, means effective to oscillate said carrier with said clamps about said second axis thereby to control the cut-

ting action of the cutter upon the work carried by the clamp, said last mentioned means including a pattern device having an adjustable cam surface, and manually operable means for adjusting said cam surface thereby to alter the cutting action of the cutter upon the work.

13. A wood shaping machine comprising, a cutter rotatably mounted about a fixed axis, a plurality of work-holding clamps each rotatably mounted about a first axis disposed in parallelism with the axis of said cutter and rockably mounted about a second axis laterally spaced from and disposed in parallelism with said first axis, means for opening and closing said clamps in a predetermined cycle, means for rotating each of said clamps about its first axis and past said cutter, means effective to oscillate each of said clamps about its second axis thereby to control the cutting action of the cutter upon the work carried by the clamp, means associated with each of said clamps for adjusting the position of the work within said clamps so that various size pieces may be accommodated therein, and means connecting all of said last mentioned means whereby they may be simultaneously adjusted by a single manual operation.

14. A wood shaping machine comprising, a substantially cylindrical shaped work-carrying member rotatably mounted about its longitudinal axis and rockably mounted about an axis laterally spaced from its longitudinal axis, a plurality of work-holding clamps spaced circumferentially about said work-carrying member, means for automatically opening and closing said clamps in a predetermined cycle, a cutter element rotatably mounted adjacent said work-carrying member, means to rotate said cutter, means for rotating said work-carrying means about its longitudinal axis so as to present each of said clamps to said cutter, means for oscillating said work-carrying member about its second axis thereby to control the action of the cutter upon the work carried by said clamps, means associated with each of said clamps for adjusting the work radially of said work-holding member so that various size work pieces may be accommodated therein, and means connecting all of said last mentioned means whereby they may be simultaneously adjusted by a single manual operation.

15. A wood shaping machine comprising, a pair of arms pivotally mounted about a common axis, a work-carrying member rotatably mounted between said arms and about an axis spaced from and in parallelism with the common axis of said arms, a plurality of work-holding clamps mounted on said work-carrying member for securing a plurality of work pieces upon said member, means for opening and closing said clamps in a predetermined cycle, a cutter rotatably mounted adjacent the periphery of said work-carrying member, means for rotating said cutter, means for rotating said work-carrying means about its axis of rotation so as to present each of the work pieces to said cutter, means to cause said arms to oscillate about said common axis so as to control the cutting action of the cutter upon the work carried by each of said clamps, means associated with each of said clamps for adjusting the position of the work within the clamp so as to accommodate the clamps for work of various sizes, and a handle rotatably mounted about the rotary axis of said work-carrying member and connected with all of said last mentioned means so that the latter may all be simultaneously ad-

justed by a single rotary movement of said handle.

16. Apparatus of the class described, comprising a base, a tool mounted in an adjustably fixed position on said base, a turret head rotatable about an axis spaced from said tool, a work holder mounted on said head and spaced from said axis so as to move past said tool in a curved path when the head rotates, and means for shifting said axis of rotation toward and from said tool during the rotation of said head to modify the curvature of the path of the work holder as it passes the tool.

17. Apparatus of the class described, comprising a base, a tool mounted on said base in a fixed position, a bearing member hinged to said base to rock about a horizontal axis lower than and offset from said tool, a horizontal shaft journaled in said bearing member above said hinge axis, a turret head mounted on and rotatable with said shaft, a plurality of work clamping devices mounted on said turret head spaced from the axis of rotation thereof and arranged to move in a curved path past said tool as the turret rotates, and means for gradually rocking said bearing member on its hinge axis as the turret rotates whereby to modify the curvature of said curved path.

18. Apparatus of the class described, comprising a base, a tool mounted in a fixed position on

5 said base, a bearing member movably mounted on said base, a shaft journaled in said bearing member, a turret head mounted on said shaft to rotate therewith, a work holder carried by said head to move in a generally circular path past said tool, means automatically closing and opening said work holder at predetermined loading and discharging points in its path before and after it passes said tool, means adjacent to 10 said bearing member for feeding a work piece to said work holder just before it reaches its loading point, and means moving said bearing member to shift the axis of said shaft toward and from said tool during the rotation of said shaft 15 whereby to modify the curvature of the path of the work holder as it passes the tool.
